ATTORNEY.

UNITED STATES PATENT OFFICE.

THOMAS JOHN AYLETT, OF RAMSGATE, ENGLAND, ASSIGNOR TO STRECHANPRES TROUSER APPLIANCE COMPANY, LIMITED, OF LONDON, ENGLAND.

TROUSERS STRETCHER.

Application filed December 10, 1923. Serial No. 679,826.

To all whom it may concern:

Be it known that I, THOMAS JOHN AYLETT, a subject of the King of Great Britain, residing at Ramsgate, Kent, England, have invented certain new and useful Improvements in Trousers Stretchers, of which the following is a specification.

This invention relates to trouser stretchers of the kind wherein the garment is stretched over a convex surface.

The object of the present invention is to provide a construction in which the lie of the garment can be observed as the pressing member is applied. Another object is to provide a construction simple to operate, and which takes up a minimum amount of room in operation. A further object is to construct a stretcher in which the pressing member is applied lengthwise of the garment, thereby eliminating the possibility of faulty creases being obtained as may occur when a hinged presser is used, the axial line of which is parallel to a longitudinal central line of the garment. A still further object is to obtain a progressive application of the pressing member lengthwise of the garment so that the garment may be straightened out as required, while pressure is being applied, and when set cannot be disturbed when final pressure is exerted. Another object is to provide a presser member for the stretcher which can be rolled up when not in use, and a further object is to construct the stretcher to support the presser when rolled up.

In the accompanying drawings is illustrated a preferred form of the present invention:

Fig. 1 is a side elevation of one form of the invention and Fig. 2 a plan thereof;

Fig. 3 shows a method of anchoring the end of the webbing beyond the pressing or convex surface, which will be used in cheaper models than that shown in Figs. 1 and 2; and

Figs. 4 and 5 show in front and side elevation respectively a clamping member made as a single casting.

Referring first to Figs. 1 and 2, the convex part of the press, generally indicated by the numeral 1, may be constructed in any suitable manner. The pressing member is formed of webbing or equivalent flexible material; in the drawings the webbing is indicated by the numeral 2 and preferably,

as shown, is in two pieces, spaced apart over the central part of the convex surface 1. The ends of the webbing at one end of the press are anchored to a bar 3, which has a removable face 4, between which and the bar the ends of the strips of webbing 2 are fixed. At each end of the bar 3 is a square pin 5, which is carried in the slotted brackets 7, there being one bracket at each side of the press, the slots, indicated at 8, being of L-shape. The brackets 7 are also provided with notches 9 shaped to receive square tongues 10 on the clamping roller 11 carried in the slotted brackets 12 at the other end of the press, so that when the clamping member 10 is pulled out of its slot, as it can be when the brackets are in the vertical position hereinafter referred to, the tongues 10 can rest in the notches 9 and the clamping member will then be supported at that end of the press.

In the construction shown in Figs. 1 and 2, the clamping member is a roller, and therefore in removing it from the press it will be preferable to roll it over the surface 1 so as to neatly take up the webbing before lodging it in the notches 9 before referred to. That end of the press where the notches 9 are, is rounded off substantially as shown in the drawings, so that the convex surface 1 is continued smoothly past the anchorage bar. At the other end of the press the convex surface is provided with an extension in the form of a roller 13. This roller is fixed on axis pins 14 so that it is rotatable therewith, the axis pins serving also as pivots for the brackets 12 before referred to, to which the brackets are also fixed.

The clamping member 11 will be engaged in the slotted brackets 12 and removed therefrom when the latter are in the vertical position, and supposing that they have been engaged in the slots of the brackets 12 and the brackets 12 are moved in the direction of the arrow 15, then it will be clear that the webbing 2 is tensioned over the convex surface 1 in direct proportion to the pressure applied to the brackets. Conveniently, this may be through a bar 16 provided with a grip 17, which connects extensions of the brackets 12 beyond the slotted portions.

To prevent inadvertent reverse rotation of the brackets 12 under tension in the webbing 2, pawls 18 are provided (preferably there is one on each side of the press) to engage in

teeth 6 formed on the respective ends of the bracket 12. The pawls, if one on each side is used as shown, are fixed to a rod 19 carrying a cranked arm 20, which in turn 5 is connected to a fixed lug 21 by means of a spring 22, so that the spring always tends to keep the pawl in engagement with the ratchet teeth 6, the tendency of the brackets to reverse under the tension in the webbing 10 2 being counteracted by the proximity of the pivot pins 19 and 14. The pawls 18 may have a thumb piece 23 so that they may be readily disengaged from the ratchets of the brackets 12 when desired.

15 In Fig. 3 a simpler construction is shown in which instead of using the more expensive anchor bars before referred to, the webbing is directly fixed to a reinforced end 24 of the convex surface 1, the reinforcement having 20 a suitable configuration, as indicated at 25, so that the ends of a pair of trousers can be interposed between the webbing and the part 25, and when the webbing has been partly pulled over the convex surface the 25 trousers can be finally adjusted and the clamping member 11 placed in the brackets 12 to apply the final tension.

If it is desired to construct a cheaper 30 press, the clamping member 11 need not be formed as a complete cylinder, as the only 35 essential is to provide a contact surface which will run smoothly over the said extension, for instance, the construction shown in Figs. 4 and 5 may be utilized. In this 40 construction a U-shaped bar is cast with a surface 26 of suitable contour, and with the tongues 10 integral as shown.

All the essentials of the clamping member 11 are provided in this construction, and 45 a considerably cheaper article may be provided.

In practice the webbing is rolled back to 50 the brackets 7 and then the garment is laid out on the convex surface; the webbing is then unrolled over the garment while pulled 55 tight, first of all clamping the garment between it and the surface and then progressively covering the garment until the clamping member can be placed in the brackets 12 60 when final tension will be applied to the webbing resulting in a stretching and pressing of the garment between the flexible member comprising the webbing strip 2 and the convex face.

55 By the use of the webbing for the tension band, increased stretching effect on the trouser is obtained, due to some extent to the stretching effect on the flexible band along with said trouser, and in practice a 60 most effective result is obtained.

I claim:—

1. A trouser stretcher comprising a convex supporting surface for a garment, a clamping member at one end of the surface, a support for removably holding the mem-

ber capable of being swung about the said end of the surface, a flexible member, formed to overlie said surface fixed at one end to the clamping member, and at its other end anchored adjacent the end of the convex surface away from the clamping member, whereby a garment laid on the convex surface may be clamped at one end between the flexible member and the surface, the flexible member being then laid lengthwise over the garment progressively from its anchored end and then placed in tension by operating the clamping member so that the garment is stretched and pressed between the flexible member and the convex surface. 70 75 80

2. A trouser stretcher comprising a convex supporting surface for a garment, a frame mounted for a swinging movement at one end of the surface, said frame including a pair of brackets one pivoted on each side 85 of the convex surface and a handle member connecting the ends of the brackets away from the pivots, a clamping member carried by said frame movable to overlie the garment, a flexible member formed to overlie the convex surface fastened by one end to said clamping member and fixed at the other end of said convex surface, whereby said overlying clamping member may be pressed towards said surface to clamp the 90 garment and the frame and clamping member rotated to stretch and press the garment between said flexible member and said convex face. 95

3. A trouser stretcher comprising a convex 100 supporting surface for a garment, a clamping member at one end of the surface, a support for removably holding the said member capable of being swung about at said end of the surface, a flexible member 105 formed to overlie said surface fixed at one end to the clamping member, and the other end fitted to a bar, a bracket at each side of the convex surface at the end away from the clamping member, said brackets being 110 slotted to receive and removably hold the bar against tension applied to the flexible member from the clamping member end of the convex surface. 115

4. A trouser stretcher comprising a convex supporting surface for the garment, a frame mounted for a swinging movement at one end of the surface, said frame including a pair of brackets one pivoted on each side 120 of the convex surface and a handle member connecting the ends of the brackets away from the pivots, a clamping member carried by said frame movable to overlie the garment, a flexible member formed to overlie the convex surface fastened by one end to 125 said clamping member, and removably fixed at the other end to a bar, a bracket at each side of the convex surface at the end away from the clamping member, said last-mentioned brackets being slotted to receive and 130

removably hold the bar against tension applied to the flexible member from the clamping member end of the convex surface.

5. A trouser stretcher comprising a convex supporting surface for the garment, a frame mounted for a swinging movement at one end of the surface, said frame including a pair of brackets one pivoted on each side of the convex surface and a handle member connecting the ends of the brackets away from the pivots, a clamping member carried by said frame movable to overlie the garment, a flexible member formed to overlie the convex surface fastened by one end

to said clamping member, and removably fixed at the other end to a bar, a bracket at each side of the convex surface at the end away from the clamping member, said last-mentioned brackets being slotted to receive and removably hold the bar against tension applied to the flexible member from the clamping member end of the convex surface, said brackets also being slotted to form a rest for the clamping member when removed from its supports.

In testimony whereof I affix my signature.

THOMAS JOHN AYLETT.
